FLOOR JACK

Albert S. Nelson Timmons, P.O. Box 136,
Livermore, Calif.Filed Oct. 25, 1963, Ser. No. 318,976
6 Claims. (Cl. 254—13)

This invention relates to a machine or apparatus for use in laying floors and which is adapted to be utilized for pulling floorboards together into abutting engagement and for holding the boards immovable while the boards are nailed or otherwise anchored to the supporting frame.

More particularly, it is an object of the present invention to provide a portable electrically driven machine for the aforescribed purpose including a wheeled frame to facilitate movement of the machine and which additionally functions as an abutment when the machine is in operation.

Another object of the invention is to provide a machine or apparatus which may be quickly engaged with and disengaged from a joist of a floor frame and a board of a floor disposed on said frame to materially reduce the labor involved in laying floor.

Various other objects and advantages of the invention will hereinafter become more fully apparent from the following description of the drawings, illustrating a presently preferred embodiment thereof, and wherein:

FIGURE 1 is a side elevational view, partly broken away, showing the floor jack in an operative position;

FIGURE 2 is an enlarged cross sectional view of the floor jack, taken substantially along a plane as indicated by the line 2—2 of FIGURE 1;

FIGURE 3 is an enlarged fragmentary substantially central longitudinal sectional view of a part of the floor jack;

FIGURE 4 is a fragmentary top plan view, partly in section, of another part thereof;

FIGURE 5 is a bottom plan view of one element of the floor jack, and

FIGURE 6 is a side elevational view of said element.

Referring more specifically to the drawings, the floor jack in its entirety and comprising the invention is designated generally 8 and includes a wheeled carriage, designated generally 9, having a frame 10 formed of a rigid piece of angle iron including a substantially horizontal top portion 11 and a depending, substantially vertical, front side or wall 12. Arms 13 are secured, as by welding, as seen at 14, in FIGURE 1, to end portions of the front wall 12. The arms 13 extend downwardly and outwardly from the frame 10, in a direction away from its top portion 11, and have outturned substantially aligned lower ends 15 forming axles on each of which is journaled a wheel 15.

A sleeve member 16 is supported on and disposed cross-wise of the intermediate portion of the top wall 11, and an electric control box 17 has an intermediate portion mounted on and secured to the sleeve 16. The control box 17 is additionally supported on the frame portion 11 by supporting legs 18. The legs 18 and the sleeve 16 are preferably secured to the top wall 11 and the bottom of the control box 17 by welding, as indicated at 19.

A conventional reversible electric motor 20 is mounted on and rises from the control box 17 and may be secured thereto in any suitable manner as by fastenings 21. A reduction gear unit 22 is mounted on the front of the motor 20 and has a forwardly extending output shaft 23 which is driven at a reduced speed from the motor and to which is secured a small sprocket wheel 24.

The sleeve or tube 16 has an externally threaded for-

2

ward end 25 which is disposed forwardly of the frame 10. A collar 26 has a central bore 27, one end of which is enlarged and internally threaded, as seen at 28, to engage on the threaded sleeve portion 25. The collar 26 includes an annular flange 29 having a threaded periphery 30.

A long feed screw 31 extends through the bore 32 of the sleeve 16 and through the bore 27. A nut 33 threadededly engages the screw 31, forwardly of the collar 26 and has a forward end engaging nonrotatively in a central opening 34 of a large sprocket wheel 35, to which said nut is secured, as by welding, as seen at 36 in FIGURE 3. The sprocket wheel 35 is disposed directly beneath the sprocket wheel 24.

The nut 33 has an annular flange 37 at its rear end which fits rotatively in a cap member 38 having a front wall 39 which is provided with a large central opening 40 in which a part of the nut 33 turnably fits. The cap 38 has an annular rearwardly extending flange 41 which is disposed around and spaced from the flange 37, and which has an internally threaded rear end 42 which threadededly engages the threaded periphery 30 for securing the cap 38 to the collar 26. As seen in FIGURE 1, setscrews 43 extend inwardly through the flange 41 and against the threaded periphery 30 for locking the cap 38 to the collar 26. A thrust bearing 44 is disposed within the cap 38 around the screw 31 and between the flanges 29 and 37. An endless chain 45 is trained around the sprocket wheels 24 and 35.

A stop or abutment 46 is secured by a fastening 47 to the forward end of the screw 31. The screw 31 has a restricted stem 48 projecting from its rear end, as best seen in FIGURE 4, which extends transversely through the intermediate portion of elongated stabilizing bar 49, which is immovably secured to said stem as by welding, as seen at 50. A clevis 51 is attached to the stem 48 beyond the bar 49 for attaching one end of a chain 52 to the screw 31.

A stay iron or anchor 53 is connected to the opposite end of the chain 52 and includes a plate 54 having depending curved spikes or cleats 55 and an upwardly extending inclined handle 56. The rear end of the chain 52 is attached by a clevis 57 to an apertured web 58 of the stay iron 53.

An electric cord 59 leads from the control box 17 to the motor 20 and is connected to an electric plug 60 which protrudes from said control box and which is adapted to be connected to a conventional electrical extension cord, not shown. An electric switch 61 which is mounted in and protrudes from the control box 17 is interposed in the electric cord 59 for stopping, starting and reversing the electric motor 20.

A chain guard 62 may be disposed over the sprocket wheel 24 and the upper part of the chain 45 and supported by braces 63 from the casing of the motor 20.

A part of a joist 64 and a part of a stud 65 is illustrated and constitutes a part of a floor frame on which a number of boards 66 are shown supported. The boards 66 may constitute a part of a subflooring, to illustrate one application and use of the floor jack 8. The top portion 11 of the frame 10 is positioned on one of the boards 66 which partially rests on the joist 64 and the front side 12 abuts a forward edge of said board 66 and an outer side of the joist 64, as seen in FIGURES 1 and 3. The anchor or stay iron 53 is forced downwardly to cause the spikes 55 to be embedded in one of the boards 66 which is located remote from the joist 64. Assuming that the plug 60 is connected to a source of electric current, as previously described, the manually actuated element of the switch 61 is swung in one direction from its intermediate "off" position as illustrated in FIGURE 2 for completing an electric circuit to the motor 20 for driving the sprocket

wheel 24, chain 45, and sprocket wheel 35 in a direction so that the nut 33, turning with the sprocket wheel 35, will feed the screw 31 from right to left therethrough, as seen in FIGURES 1 and 3. The stabilizer bar 49 is disposed in sufficiently close proximity to the flooring 66 to prevent rotation of the screw 31 and to insure feeding of the screw through the nut 33. The thrust bearing 44 absorbs the thrust of the nut 33 toward the collar 26 during this movement of the screw. As the screw is slowly advanced from right to left the chain 52 is initially tensioned, after which the screw and chain exert a pull on the stay iron or anchor 53 for drawing the boards 66 located between the joist 64 and the board to which said anchor is secured, toward one another and into tight abutting engagement. When this is accomplished, the switch 61 is returned to an "off" position to de-energize the motor 20, and while the boards 66 are thus held tightly together said boards are secured to the framing 64, 65. The switch 61 is then swung in the other direction for causing the motor to be driven in other direction for feeding the screw 31 in the opposite direction or from left to right of FIGURES 1 and 3 through the nut 33 until slack is produced in the chain 52. A downward pressure can then be exerted on the handle 56 for rocking the stay iron 53 counterclockwise, as seen in FIGURES 1 and 6, for disengaging the spikes 55 from the flooring 66.

The bar 49 also functions as a handle for propelling the jack 8 from one location to another on the wheels 15 after disengagement of the frame 10 from the joist 64.

Various modifications and changes are contemplated and may obviously be resorted to, without departing from the function or scope of the invention as hereinafter defined by the appended claims.

I claim as my invention:

1. A floor jack comprising a frame member including a top portion and a depending front wall, a reversible electric motor supported above and secured to said top portion, means secured to said frame and disposed crosswise thereof, a nut swivelly supported by said means forwardly of the frame, a feed screw extending threadedly

through said nut and supported thereby crosswise of the frame with a part of said feed screw extending between the frame and electric motor, a stay iron connected to one end of said screw and having depending spikes adapted to be anchored in a flooring board, and means including a sprocket wheel and chain drive forming a driving connection between the electric motor and said nut for revolving the nut in one direction when the motor is energized for feeding said screw through the nut in a direction for pulling the stay iron toward said frame.

10 2. A floor jack as in claim 1, a stabilizing bar rigidly secured to and disposed crosswise of said screw end to prevent rotation of the screw with said nut.

15 3. A floor jack as in claim 2, a pair of transversely spaced wheels, means connecting said wheels to the frame and combining therewith to form a carriage, and said stabilizing bar constituting a handle for propelling the jack on said wheeled carriage.

20 4. A floor jack as in claim 1, said first mentioned means comprising a sleeve supported on and disposed crosswise of the frame, a collar detachably secured to a forward end of said sleeve, a cap detachably secured to said collar, said nut having a part rotatively confined in said cap.

25 5. A floor jack as in claim 4, and a thrust bearing interposed in said cap between said part of the nut and a part of said collar.

6. A floor jack as in claim 5, said sleeve and collar having aligned bores through which a part of said feed screw extends.
